UNITED STATES PATENT OFFICE

109,340

DESIGN FOR A CABINET FOR PHONOGRAPH OR THE LIKE

Henry T. Roberts, Chicago, Ill., assignor to J. P. Seeburg Corporation, Chicago, Ill., a corporation of Illinois

Application January 17, 1938, Serial No. 74,359

Term of patent 7 years

To all whom it may concern:

Be it known that I, Henry T. Roberts, a citizen of the United States and a resident of Chicago, in the county of Cook and State of Illinois, have invented a new, original, and ornamental Design for a Cabinet for Phonograph or the like, of which the following is a specification, reference being had to the accompanying drawings forming part thereof.

I claim:

The ornamental design for a cabinet for phonograph or the like substantially as shown.

HENRY T. ROBERTS.
